[57] CLAIM

The ornamental design for a tapered traction stud, as shown and described.

DESCRIPTION

FIG. 1 is a top plan view of a tapered traction stud, showing our new design according to the present invention;

FIG. 2 is a bottom plan view thereof;

FIG. 3 is a front elevational view as viewed in FIG. 1, the rear elevational view viewing a mirror image; and,

FIG. 4 is a side elevational view taken from the right side of FIG. 1, it being understood that the left hand elevational opposite side view is a mirror image thereof.
